CLAIM

We claim, the ornamental design for an infusion pump rack,
as shown and described herein.

DESCRIPTION

FIG. 1 illustrates a perspective view of an infusion pump
rack, according to one embodiment of the invention.

FIG. 2 illustrates a front view of the infusion pump rack
shown in FIG. 1.

FIG. 3 illustrates a rear side view of the infusion pump rack
shown in FIG. 1.

FIG. 4 illustrates a left side view of the infusion pump rack
shown in FIG. 1.

FIG. 5 illustrates a right-side view of the infusion pump rack
shown in FIG. 1.

FIG. 6 illustrates a top view of the infusion pump rack
shown in FIG. 1.

FIG. 7 illustrates a bottom view of the infusion pump rack
shown in FIG. 1.

FIG. 8 illustrates a perspective view of an infusion pump
rack, according to a second embodiment of the invention.

FIG. 9 illustrates a front view of the infusion pump rack
shown in FIG. 8.

FIG. 10 illustrates a rear view of the infusion pump rack
shown in FIG. 8.

FIG. 11 illustrates a left side view of the infusion pump rack
shown in FIG. 8.

FIG. 12 illustrates a right-side view of the infusion pump
rack shown in FIG. 8.

FIG. 13 illustrates a top view of the infusion pump rack
shown in FIG. 8; and,

FIG. 14 illustrates a bottom view of the infusion pump rack
shown in FIG. 8.

(Continued)

The broken lines in the drawings illustrate portions of the infusion pump rack and form no part of the claimed design. Additionally, the infusion pump rack is not limited to the scale shown herein.
